UNITED STATES PATENT OFFICE

2,328,379

ARTIFICIAL TOOTH

Reiner W. Erdle, Chicago, Ill., assignor to Dental Research Corporation, Chicago, Ill., a corporation of Illinois

Application April 10, 1940, Serial No. 328,912

5 Claims.

(Cl. 32—10)

This invention relates to artificial teeth, and more particularly to an improved pinless retention therefor.

While pinless forms of retention for artificial teeth have been previously proposed, the prior forms of pinless retention have not gone into general use because they have not been as practical as desired, and because it is impracticable to produce teeth of this type in the rigid molds used by most manufacturers.

With pin retention, the pins have usually been made of platinum, gold plated nickel, or the like, which makes the retention an expensive matter, not only on account of the material, but also on account of the many laborious operations required to produce pin teeth. Also, where a pin retention is employed, the attachment of the tooth is localized, and there is a tendency for the tooth to split at the point where the pins are anchored when strain is applied to the tooth.

Another disadvantage of pin teeth is that in close bite cases, the pins are in the way, which interferes with the proper setting up of the teeth. Also, due to the fact that the pins have to be anchored in the bulkiest part of the tooth, there is interference with the production of a natural lingual aspect of the tooth.

In the case of applying stains to teeth in order to shade them to suit the individual case, it is necessary to pass them through the furnace to bake on the stains. It is not practicable to do this with the ordinary pin teeth because the base metal pin will be oxidized. It has, therefore, been necessary to use platinum pin teeth which are expensive and which are not ordinarily carried in stock in dental supply houses.

Moreover, where pins are soldered into the teeth, if a high fusing stain is employed the high temperatures required may affect the solder or even burn the gold plating off of the pins. On the other hand, if a low fusing stain or glaze is employed, it is subject to attack by the saliva.

One of the main objects of the present invention is to provide an improved form of retention which is relatively inexpensive, due particularly to the fact that it makes it possible to dispense with pins and the like and the laborious operations required to produce pin teeth; also, a formed retention which will secure the tooth firmly in place and with which the strength of the tooth is greatly increased.

Another object of the invention is to provide a retention which is adapted to eliminate localization of the attachment of the tooth which has occurred with pin retentions, and which is also

adapted to eliminate, when strain is applied to the tooth, the tendency of the tooth to split at the points where the pins are anchored in teeth with pin retention.

5 It is also an object of the invention to provide a formed retention that will permit an irregular set-up of the teeth to simulate natural conditions; also, a formed retention that will minimize the risk of exposing retention cavities and 10 the like on account of such irregular set-up, and a formed retention adapted to avoid the problems of baking on stains and the like where retention pins have been employed.

A further object of the invention is to provide 15 an improved retention which need not have pins or the like in the way to interfere with the setting up of the teeth, and which improved retention will lend itself to the production of a natural lingual aspect of the tooth; also, an improved retention which will eliminate the difficulties heretofore presented in passing teeth with pin retention through the furnace to bake on the stains for shading the teeth to suit the individual case.

20 Another object of the invention is to provide an improved form of retention which will permit the denture base material to extend into the body of the tooth and approach the incisal edge where the force of biting is applied, thereby allowing 25 positioning of the retention closer to the point of application of the force than with pin retention, with consequent less likelihood of the tooth coming loose.

Further objects and the precise features and 30 advantages of the invention will be apparent from the following detailed description, taken in connection with the accompanying drawing in which:

Figure 1 is a fragmentary front elevation showing two teeth with formed retention embodying the present invention set in the base material of the denture;

Figure 2 is a side view of one of the teeth embodying the formed retention of the present invention on an enlarged scale;

Figure 3 is a rear elevation of the tooth shown in Figure 2;

Figure 4 is a generally horizontal section taken on the line 4—4 of Figure 3;

Figure 5 is a front view of a posterior tooth embodying the present invention;

Figure 6 is a plan view of the tooth shown in Figure 5 on an enlarged scale; and

Figure 7 is a perspective view, partially broken away and in section, showing the details of the retention cavities and the generally V-shaped

retention rib of the tooth shown in Figures 5 and 6, also on an enlarged scale.

Referring now in detail to the drawing, the reference character 10 (Figure 1) indicates fragmentarily a denture base or plate formed of any suitable denture material. The teeth shown for purposes of illustration at 11 and 12 are attached to the base or plate 10 by molding the denture base or plate material thereto, as well understood in the art.

While the retention of the present invention is not limited to anterior teeth but may, within the broader aspects of the invention, be formed on posterior teeth as will hereinafter appear, the tooth 11, which is shown in detail and on an enlarged scale in Figures 2, 3, and 4, is one of the anterior teeth shown in Figure 1. It may be formed of porcelain, or any porcelain-like or other suitable tooth material, and is preferably molded in a flexible mold in the manner more fully described in my copending application, Serial No. 101,740, filed September 21, 1936, now Patent No. 2,196,258, issued April 9, 1940.

The use of a flexible mold and the method of my above identified copending application make it a simple matter to mold the teeth with the retention of the present invention formed integrally therewith, thereby overcoming the obstacles to molding the teeth with this retention in rigid molds. It is to be understood, however, that I do not intend to limit the tooth and retention of the present invention to formation in a flexible mold or by the method referred to, any suitable mold means and any suitable method of forming the tooth and retention thereon being contemplated within the scope of the present invention.

The front or labial side of the tooth 11 is indicated at 14, and the rear or lingual side is indicated at 15. The front and rear surfaces 14 and 15 are marked and of an extent to simulate the corresponding surfaces of a natural tooth. The incisal edge of the tooth is indicated at 16, and the opposite marginal edge of the front side of the tooth may be indented at 18 to enter the denture base material as shown in Figure 1.

The back of the tooth has a tongue-like portion or generally V-shaped rib 20 formed integrally therewith. The surface 21 of this tongue-like portion 20 is inclined from the upper edge of the lingual surface 15 to the upper edge of the front or labial surface 14. The tongue 20 is disposed substantially centrally between the opposite sides of the tooth and is of generally dove-tail shape in horizontal section as shown in Figures 3 and 4, with the wider end of the tongue disposed inwardly or toward the rear side of the tooth and the generally vertical sides 25 of the tongue converging outwardly to the narrower end of the tongue which is disposed outwardly or toward the front of the tooth.

The generally vertical retention surfaces 22 are preferably not coplanar, but are inclined, as shown in Figure 4, away from the labial surface of the tooth. This permits an irregular setup of the teeth to simulate natural conditions, and minimizes the risk of exposing the retention cavities on account of such irregular setup. The lower ends of the surfaces 22 extend down below the upper edge of the rear or lingual surface 15, where they meet the other sides 23 of the retention cavities. These other sides 23 of the retention cavities, one of which is thus provided on each side of the tongue 20, may follow the curvature of the rear or lingual surface 15, or they

may be of any other suitable or preferred form.

With the construction thus far described it will be apparent that a retention cavity is formed on each of the opposite sides of the tongue-like portion 20 and that each of these retention cavities has three sides, one side being formed by the adjacent side 25 of the tongue 20 and the other sides being formed by the retention surfaces 22 and 23. These retention cavities are thus of generally pyramidal form.

Each of the retention surfaces 25, 22, and 23 of each retention cavity has a plurality of small serrations molded into the same. In the illustrated embodiment of the invention the retention serrations on the opposite sides of the tongue 20 are in the form of generally vertical grooves 28, preferably with the grooves toward the front of greater width for the easy flow of the base or plate material into the same. The retention serrations on the retention surfaces 23 are shown in the form of grooves 29 inclined outwardly away from the opposite sides of the tongue 20; also, preferably with the grooves 29 toward the front of greater width for the easy flow of the base or plate material into the same. The retention means on the surfaces 22 are shown in the form of grooves 30 inclined upwardly from the opposite sides to the tongue 20.

The improved retentive effect of the formed retention of the present invention is due to the combined influence of the dovetail shape of the tongue-like portion 20 together with the effect of the many small serrations which are molded into the surfaces of the retention cavity. In order to secure an additional degree of adhesion, the retention surfaces are all preferably sand blasted or otherwise treated to remove the glaze resulting from firing.

The generally pyramidal shape of the retention cavities and the resulting generally pyramidal shape of the denture base material as it enters and is molded into these cavities permit easy flow of the denture base or plate material into the cavities when the denture is molded and, at the same time, the serrations produce an interlocking effect which prevents the material from being pulled out again when force is applied to the tooth. The extension of the retention surfaces 22 down below the upper edge of the rear or lingual surface 15 where they meet the sides 23 of the retention cavities, extends the inner ends of the retention cavities into the body of the tooth to points where they more closely approach the incisal edge of the tooth where the force of biting is applied. In this way, the retention is closer to the point of application of the force than with pin retention, with consequent less likelihood of the tooth coming loose.

In the posterior tooth shown in Figures 5, 6, and 7, the labial side is indicated at 40, the lingual side at 41, and the surface where the biting force is applied is indicated at 42. The surfaces of the tooth are shaped and marked to simulate the corresponding surfaces of a natural tooth, or otherwise as desired.

The inwardly tapering retention cavities 43 extend inwardly into the body of the tooth into relatively close proximity to where the biting force is applied at 42, and these cavities are separated by the generally V-shaped rib or tongue 45 which is molded integrally with the tooth. The rib 45, in addition to being V-shaped as shown, and as already more fully described in connection with the preceding embodiment of the invention, is undercut at 46 further to improve

the retention. The surfaces 48 of the cavities 43 have a plurality of small retention serrations molded into the same, these retention serrations being shown in the form of grooves 50. As in the preceding embodiment of the invention, the retention areas of the tooth preferably have the glaze, resulting from firing, sand blasted or otherwise removed therefrom.

The particular angle of the retention grooves shown in the drawing was determined partly by tests of the efficiency of the retention and partly by expediency in the production of the metal master teeth. The arrangement shown is deemed entirely practicable, but it is to be understood that the angle of the retention grooves may be varied considerably from that shown and described, and it is to be also understood that where the retention serrations are in the form of grooves, these grooves may be of the saw-tooth type or of a different shape as, for instance, grooves of square cross section or of other form as suitable and desired.

With the present invention it is not necessary to connect the two retention cavities inside of the tooth so that the denture base material can actually come together from each side. The retention serrations in the cavities cause the denture base material to become locked into the cavities, and, in combination with this, the dovetailed shape of the center tongue or rib is also effective in preventing displacement of the tooth in an interior direction when force is applied. Of course undercutting of the center tongue or rib is contemplated as herein disclosed.

In some instances it may be desirable to have the surfaces 22 curved in the direction from gingival to incisal, and therefore such curvature is contemplated within the scope of the present invention. It is also possible that it might be advantageous in some instances to curve these surfaces in the other direction, i. e., from the median line of the tooth to the medial or distal, and that too is contemplated within the scope of the present invention.

I do not intend to be limited to the precise details shown or described.

I claim:

1. An artificial tooth having formed pinless retention molded integrally therewith and comprising a pair of generally pyramidal shaped retention cavities, a generally dovetail shaped rib between said cavities, the front sides of said cavities being inclined away from the labial surface of the tooth and generally vertically disposed, said cavities being disconnected and the inner ends thereof extending inwardly into the body of the tooth inwardly beyond the base of the lingual surface of the tooth and into relatively close proximity to where the biting force is applied, a plurality of generally laterally directed and inclined grooves molded into the front surfaces of said cavities, generally vertical grooves molded into the opposite sides of the generally dovetail shaped rib, and retention grooves molded into the other sides of said retention cavities.

2. A unitary artificial side retention denture tooth comprising a body having substantially complete labial and lingual surfaces and a generally vertically disposed rib extending between said lingual and labial surfaces and having a gingival surface sloping from the labial gingival downward to the lingual gingival, said rib decreasing in width from said lingual surface toward said labial surface and defining with the lingual and labial portions of the tooth body a

pair of substantially triangular retention cavities at opposite sides of said rib open at the sides of the body, each of said cavities being provided at the labial surface thereof with retention serrations extending outward from said rib, the latter being provided at the opposite sides thereof with retention serrations.

3. A unitary artificial side retention denture tooth comprising a body having substantially complete labial and lingual surfaces and a generally vertically disposed rib extending between said lingual and labial surfaces and having a gingival surface sloping from the labial gingival downward to the lingual gingival, said rib decreasing in width from said lingual surface toward said labial surface and defining with the lingual and labial portions of the tooth body a pair of substantially triangular retention cavities at opposite sides of said rib open at the sides of the body, each of said cavities being provided at the labial surface thereof with retention serrations extending outward from said rib, the latter being provided at the opposite sides thereof with retention serrations and each of said recesses being provided at the lingual surface thereof with retention serrations substantially perpendicular to the serrations of said rib.

4. A unitary artificial side retention denture tooth comprising a body having substantially complete labial and lingual surfaces and a generally vertically disposed rib extending between said lingual and labial surfaces and having a gingival surface sloping from the labial gingival downward to the lingual gingival, said rib decreasing in width from said lingual surface toward said labial surface throughout its full height and defining with the lingual and labial portions of the tooth body a pair of substantially triangular retention cavities at opposite sides of said rib open at the sides of the body, each of said cavities being provided at the labial surface thereof with retention serrations extending outward from said rib, the latter being provided at the opposite sides thereof with retention serrations disposed substantially perpendicular to said labial surface serrations and each of said recesses being provided at the lingual surface thereof with retention serrations substantially perpendicular to the serrations of said rib.

5. A unitary artificial side retention denture tooth comprising a body having substantially complete labial and lingual surfaces and a generally vertically disposed rib extending between said lingual and labial surfaces and having a gingival surface sloping from the labial gingival downward to the lingual gingival, said rib decreasing in width from said lingual surface toward said labial surface throughout its full height and defining with the lingual and labial portions of the tooth body a pair of substantially triangular retention cavities at opposite sides of said rib open at the sides of the body, each of said cavities being provided at the labial surface thereof with retention serrations extending outward from said rib at an inclination inward and toward the labial gingival surface of the body, said rib being provided at the opposite sides thereof with retention serrations disposed substantially perpendicular to said labial surface serrations and each of said recesses being provided at the lingual surface thereof with retention serrations substantially perpendicular to the serrations of said rib.

REINER W. ERDLE.
